(57) **CLAIM**

The ornamental design for a hair iron, as shown and described.

DESCRIPTION

FIG. 1 is a top view of the hair iron showing my new design;

FIG. 2 is a front view thereof;

FIG. 3 is a bottom view thereof;

FIG. 4 is back view thereof;

FIG. 5 is an enlarged perspective view of the present invention held in an open position;

FIG. 6 is a front view thereof, shown in an open position;

FIG. 7 is a sectional view taken along lines 7—7 in FIG. 6;

FIG. 8 is a right side view of the present invention; and,

FIG. 9 is a left side view thereof.

The broken lines showing the cord, plug, hand and circular elements are for illustrative purposes only and form no part of the claimed design.
